UNITED STATES PATENT OFFICE.

JAMES H. RAND, OF NORTH TONAWANDA, NEW YORK.

INDEX DEVICE.

1,227,662.

Specification of Letters Patent. Patented May 29, 1917.

Application filed July 17, 1916. Serial No. 109,765.

To all whom it may concern:

Be it known that I, JAMES H. RAND, a citizen of the United States, and resident of North Tonawanda, in the county of Niagara and State of New York, have invented new and useful Improvements in Index Devices, of which the following is a specification.

This invention relates to indexes of the so-called visible index type having a frame in which are supported a series of cards in spaced relation with their free edges projecting one beyond another.

In the accompanying drawings which illustrate certain embodiments of the invention,

Figure 1 is a face view of part of an index containing the invention, partly broken away;

Fig. 2 is an enlarged detail in vertical cross section of one of the sheaths and the card removably held thereby;

Fig. 3 is a face view of the form of card shown in Fig. 2, the same being unfolded;

Fig. 4 is a perspective view of part of said card folded in the manner hereinafter described;

Fig. 5 is a sectional detail view similar to Fig. 2 showing a modification of the invention; and

Fig. 6 is a similar sectional view showing another modification.

A represents the index frame which may be of usual construction and has an inwardly turned guide flange α at each side forming a pair of opposed guide channels for receiving the card supporting means.

B represents the card which is made with two parallel and opposite folds near one margin, said folds being along scored or otherwise weakened on defined lines b' and b'' , and forming an indicator section b and an intermediate section b^3 by which the indicator section b is connected to the body of the card B. By thus folding such sections in opposite directions on parallel lines, the front face of the indicator section b is formed of the front face of the card, so that in placing the inscription on the indicator section b the writing whether done by hand or by machine, is on the face of the card, and so that when the card is removed from the sheath it may be straightened or flattened out for the purpose of filing, with the inscription appearing on the margin of the

front face of the card. In the form shown in Figs. 2, 3 and 4 the two sections b and b^3 are of substantially the same breadth.

Each card is held by a sheath of transparent resilient material such as sheet celluloid having a closed front face c and inwardly turned retaining lips lengthwise of its longer sides. In the form shown in Fig. 2, the lower retaining lip is rearwardly bent as shown at c' and thence inwardly bent as shown at c^2 , and the upper retaining lip is rearwardly bent as shown at c^3 and inwardly bent as shown at c^4 , said retaining lips c^2 and c^4 overlapping each other in substantially parallel relation with the lip c^4 on the outer or rear side. The oppositely folded sections of the card are held in the sheath, in the form shown in Fig. 2, with both the indicator section b and the intermediate section b^3 held in the space between the front face c of the sheath and the forward turned lip c^2 , the fold b^2 extending around the edge of lip c^2 and the body of the card B extending outward from the sheath through the space between the two lips. Thus, the card body extends from the rear side of the sheath while the indicator section b is offset from the plane of the card body by means of the connecting or intermediate section b^3 , so that the face of the indicator section is positioned close to the front face c of the sheath.

In the form shown in Fig. 5, the lower retaining lip c' of the sheath is bent backwardly terminating as shown without any inwardly bent portion corresponding to c^4 , while the upper lip composed of the parts c^3 and c^4 is the same as in Fig. 2. In this form the opposite folds of the card may be placed closer together forming an indicator section b , as before, and a much narrower intermediate section b^3 by which the indicator section is connected to the card body and offset forwardly therefrom.

In the form shown in Fig. 6, the sheath has the rearwardly and inwardly bent retaining lips c' , c^6 and c^8 , c^6 , the parts c^6 and c^8 not overlapping each other as in Fig. 2 but terminating short of each other as shown. In this form the card used should have the opposite folds so spaced apart that the intermediate section b^3 is of sufficient breadth to extend from the bottom of the sheath up over the edge of lip c^6 , the indi-

cator section *b* being offset from the body of the card as before toward the front face *c* of the sheath.

In any of the forms the body of the card 5 extends outward from the sheath through the space between the retaining lips and the indicator section *b*, formed by the opposite folds near the margin of the card, and connected to the body of the card and offset 10 therefrom by the intermediate section *b*², constitutes the supporting means by which the card is removably attached to the sheath.

The term "card" as used throughout the specification and claims is used to denote a 15 sheet of cardboard, paper, or any suitable material whether comparatively thick or thin and is not to be construed as a term of limitation signifying necessarily a sheet of cardboard or like comparatively stiff ma- 20 terial.

I claim:

1. An index device comprising a sheath having retaining lips, and a card having two parallel and opposite folds near one 25 margin, forming an indicator section the front face of which is formed of the front face of the card, and an intermediate section by which the indicator section is connected to and offset from the body of the 30 card, the indicator section being removably held within the sheath, and the body of the card extending outward from the sheath through the space between the retaining lips.

2. An index device comprising a sheath having retaining lips, and a card having two parallel and opposite folds near one margin, forming an indicator section the front face of which is formed of the front 40 face of the card, and an intermediate section by which the indicator section is connected to and offset from the body of the card, the indicator section being removably held within the sheath near the front there- 45 of, and the body of the card extending outward from the sheath through the space at the rear of the sheath between the retaining lips.

3. An index device comprising a sheath having retaining lips, one overlapping the 50 other at the rear side of the sheath, and a card having two parallel and opposite folds near one margin, forming an indicator section the front face of which is formed of the front face of the card, and an intermediate 55 section by which the indicator section is connected to and offset from the body of the card, the indicator section being removably held within the sheath near the front thereof and the body of the card extending outward 60 from the sheath through the space at the rear of the sheath between the retaining lips.

4. An index device comprising a sheath having retaining lips, and a card having two parallel and opposite folds near one 65 margin, forming an indicator section the front face of which is formed of the front face of the card, and an intermediate section by which the indicator section is connected to and offset from the body of the 70 card, said two sections being of substantially the same breadth, the indicator section being removably held within the sheath and the body of the card extending outward 75 from the sheath through the space between the retaining lips.

5. An index device comprising a sheath having inturned retaining lips lying substantially parallel and overlapping each other, and a card having two parallel and 80 opposite folds near one margin, forming an indicator section the front face of which is formed of the front face of the card, and an intermediate section by which said indicator section is connected to and offset from the 85 body of the card, said two sections being of substantially the same breadth and being both held in the space between the front face of the sheath and the forward inturned lip, and the body of the card extending out- 90 ward from the sheath through the space between the two lips.

Signed by me at Boston, Massachusetts, this 5th day of July, 1916.

JAMES H. RAND.
